UNITED STATES PATENT OFFICE

JAMES C. STEEN AND CHARLES L. WARNER, OF CINCINNATI, OHIO, ASSIGNORS TO THE CINCINNATI SHAPER COMPANY, OF SAME PLACE.

SHAPING OR PLANING MACHINE.

SPECIFICATION forming part of Letters Patent No. 656,795, dated August 28, 1900.

Application filed May 9, 1900. Serial No. 16,018. (No model.)

To all whom it may concern:

Be it known that we, JAMES C. STEEN and CHARLES L. WARNER, citizens of the United States, and residents of the city of Cincinnati, county of Hamilton, and State of Ohio, have invented a certain new and useful Improvement 5 in Shaping or Planing Machines, of which the following is a full, clear, and exact description, reference being had to the accompanying drawings, which form a part of this specification.

Our invention relates to an improvement in shaping-machines, and is designed to furnish a means by which the downfeed of the 15 tool may be regulated automatically.

The character of the improvement will appear more fully as we proceed with the description.

In the drawings, Figure 1 is a top plan view 20 of an ordinary shaping-machine, partly shown in section, with our improvement attached. Fig. 2 is a side elevation of the same, also partly in section. Fig. 3 is a cross-section of the ram on the line 4-4 of Fig. 1. Fig. 4 is 25 a detail of the pawl which controls the downfeed of the tool.

Like letters of reference indicate identical parts in the various figures.

The ram A is mounted on the column C and 30 is operated in the usual manner by an oscillating arm (not shown in the drawings) connected to said ram A by the usual adjustable block B or in any other convenient manner. The tool-carrying slide D is mounted at the 35 forward end of the ram A in the usual manner and is operated by the feed-screw a. A bevel-gear b is splined to the feed-screw a and meshes with a bevel-gear on the short shaft c, which is mounted in the end of the 40 ram. A second short shaft e is mounted in any convenient manner in the ram A at right angles to the shaft c and has keyed to it at one end the bevel-gear d', meshing with the bevel-gear d, keyed to the shaft c. Loosely 45 mounted on the shaft e is a rocker f, carrying the spring-controlled reversible pawl n, which normally engages with a ratchet-wheel n', keyed to the shaft e. Loosely mounted on the bearing of the shaft e is a sleeve i, having 50 a projecting flange i', which covers the

teeth of the ratchet-wheel n'. The projecting flange i' does not cover all of the teeth of the ratchet-wheel n', but leaves some of them exposed to the action of the pawl n, as seen in Fig. 4. Loosely mounted on the shaft 55 e is a depending arm j, which is adapted to engage with extending lugs f' f' on the end of the rocker f, so that the rocking of the arm j will be communicated to the rocker f. A bracket k, carrying a pin l, is adjustably 60 mounted on a bar m, which is secured to the column of the machine.

Referring now to the sleeve i, as we said before the flange i' of this sleeve i only extends part way around the ratchet-wheel n', 65 a portion of it being cut away, so as to leave a number of teeth of the ratchet uncovered, this number being determined by the angle through which the rocker f is intended to operate. The pawl n is of such a shape that 70 when in engagement with the teeth of the ratchet it will turn the ratchet if moved in one direction, but will simply ride over said teeth if moved in the opposite direction. On the return stroke of the ram A the arm j is 75 struck by the pin l, and by striking one of the lugs f' communicates this rocking motion to the pawl n, which causes the ratchet-wheel n' to be turned and through it the shafts e and c, thus causing the screw a to feed down. 80 If the whole throw of the pawl n causes a too-rapid feed, the sleeve i may be adjusted so that fewer teeth are affected by the pawl n, thus decreasing the feed. The ends of the flange i' of the sleeve i are chamfered off, as 85 seen in Fig. 4, so as to permit the pawl n to ride freely from the teeth onto the teeth-covering flange i'. It is readily apparent that the sleeve i may be so turned that no teeth of the ratchet-wheel n' will be affected by 90 the rocking of the pawl n, in which case the screw a will not be fed down at all.

Having thus described our invention, what we claim, and desire to secure by Letters Patent, is—

1. In a shaping or planing machine for automatically operating the downfeed of the tool, a shaft, a rocker carried thereon, a pawl carried by said rocker, a ratchet-wheel keyed to said shaft, a sleeve partially covering said 95 100

ratchet, mechanism whereby said rocker is oscillated at each reciprocation of the ram, and gearing intermediate said shaft and feed-screw whereby said feed-screw is operated, substantially as shown and for the purpose described.

2. In a shaping or planing machine for automatically operating the downfeed of the tool, a shaft with gearing intermediate said shaft and the feed-screw, a rocker carried by said shaft, a pawl carried by said rocker, a ratchet-wheel keyed to said shaft, a loose sleeve partially covering said ratchet, an arm loosely mounted on said shaft and engaging lugs on said rocker, in combination with a

pin carried by an adjustable slide on the column of the machine, substantially as shown and described.

3. In a shaping or planing machine, the feed-screw *a*, shaft *e*, and gearing intermediate the two, the rocker *f*, the pawl *n*, the ratchet-wheel *n'*, the loose sleeve *i*, the dependent arm *j*, in combination with the bracket *k*, carrying the pin *l*, substantially as shown and for the purpose described. 20

JAMES C. STEEN.
